Primary Examiner — Catherine Ho*(74) Attorney, Agent, or Firm* — Daniel M. Cohn;
Howard M. Cohn(57) **CLAIM**

The ornamental design for a luggage tag as shown and described.

DESCRIPTION

FIG. 1 is a perspective view of a luggage tag showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a perspective view of a luggage tag shown in an open state; and,

FIG. 10 is an enlarged detailed view of portion 10 in FIG. 1.

The broken lines depict portions of the luggage tag and form no part of the claimed design.

1 Claim, 10 Drawing Sheets(56)
